SPINNING FRAME

Walter S. Eastman, Glendale, R. I., assignor to
Stillwater Worsted Mills, a corporation of
Rhode Island

Application February 6, 1941, Serial No. 377,633

17 Claims. (Cl. 19—130)

My invention relates to spinning frames.

It has among its objects to provide an improved pressure mechanism therefor of the type adapted to divorce the twisting of the yarn from the drafting function of the front rolls. A further object is to provide an improved pressure mechanism of this type having an improved resilient pressure plate and having this plate so mounted in an improved manner as to enable the plate to fit the top front roll very closely in such an improved manner as to increase the effectiveness of the pressure mechanism while also adapting it to use with top front rolls of various forms without loss of effectiveness. A still further object of my invention is to provide such an improved plate structure which, while having the above advantages, also may be produced markedly less expensively than the rigid plates heretofore provided. These and other objects and advantages of my improvements will, however, hereinafter more fully appear.

In the accompanying drawing, I have shown for purposes of illustration one embodiment which my invention may assume in practice.

In this drawing,

Figure 1 is an end elevation of a spinning frame equipped with my improvements;

Fig. 2 is a partial front elevation of such a frame;

Fig. 3 is a sectional view on line 3—3 of Figure 1;

Fig. 4 is an enlarged end elevation of my improved pressure means in operative position, and

Fig. 5 is an enlarged perspective view of the same, the parts thereof being shown vertically spaced prior to assembly in order to facilitate illustration.

In this illustrative construction, I have shown a spinning frame of standard form including a usual carriage stand 1 having usual drafting mechanism thereon including lower front fluted rolls 2 and cooperating top front rolls 3, herein cork covered, as well as usual closed pigtail guides 4 disposed above the caps 5 of usual whirled bobbins 6; a usual pressure frame 7 being provided for each pair of rolls 2, 3 and normally biased to operative position and pivoted at 8 on the front saddle bar 9 of the stand 1, while the pressure means, carried as usual on the front end of the frame 7, are of an improved construction and cooperate in an improved manner with the roll 3, all as hereinafter more fully described.

Referring more particularly to these pressure means, it will be noted that a resilient pressure

plate 10 is provided for cooperating with each upper front roll 3. This plate 10 is preferably formed of suitable resilient sheet material such for example as spring steel and is preferably also of the same width as the roll 3 and also flexible and adapted to conform to the bottom of roll 3 over a substantial length when pressing the yarn against the latter roll, as shown in Figure 1. As shown in Figure 5, this plate 10 is normally flat and also longer than the rigid plates heretofore provided. It also is provided with like curved extensions 11 and 12 on its front and rear edges. Herein, these extensions are each bent downwardly and inwardly from the same sheet forming the body of the plate 10 in such manner as to provide a front yarn supporting surface 13 along the front edge of the plate, corresponding to the enlarged rigid curved lip heretofore provided on rigid plates, and a corresponding and identical surface 14 on the rear edge of the plate adapted to function either as front or rear portion as hereinafter described. Further, it will be observed that oppositely directed spring flanges 15 are also provided on the extensions 11, 12 below these surfaces and spaced below each end of the body portion of the plate 10.

Spaced below the plate 10 is also a normally flat supporting plate 16, preferably also of suitable spring metal and of the same width as the plate 10; this plate 16 herein being carried on the front end of the frame 7 and carrying the plate 10 and pressing the latter against the roll due to the action of the frame 7. As shown, the plate 16 is provided with a round aperture 17 spaced centrally from its sides and ends and adapted to receive therein and to be supported on, the upper end of the usual ball 18 provided on the usual upstanding front end of the pressure frame 7. As shown, this plate 16 is also provided at its opposite ends with upwardly and outwardly angularly directed end flanges 19 received in the curved extensions 11 and 12 on the plate 10 and underlying and engaging and supporting inner curved faces of the tops of these extensions, while the flanges 15 on these extensions support the plate 16 below these flanges 19.

In the operation of my improved construction, due to the provision of the improved spring plate 10 and the action of the pressure frame 7, the plate 10 is flexed to conform to the adjacent portion of the periphery of the roll 3 when pressed against the latter. Thus, a desirable close fit between the plate 10 and the roll is obtained in such manner as to maintain the fibres

in the desired relation as they pass to the front yarn supporting surface 13 on the front sheet metal extension 11. Further, it will be apparent that the upper part of the corresponding surface 14 on the extension 12 acts to direct the yarn between the roll 3 and the plate 10, while the front yarn supporting surface 13 acts to support the yarn when free from pressure in such manner as to space the beginning of twist from the point where the yarn emerges from between the roll 3 and plate 10 as usual in such devices, so that the beginning of twist is located directly above the closed pigtail guide 4 in the desired manner. Due to the mounting of the plate 10 on the supporting member 16, and the mounting of the latter on the ball 18, it will also be apparent that the plate 10 is properly supported at its opposite ends and that the two members 10 and 16 are free to accommodate themselves to one another in different relations, while being maintained in assembled relation by the action of the flanges 15. The universal support for the plate 16 is also such as to maintain the plate 10 in the desired relation to the bottom of the roll 3 throughout the operation of the mechanism. It will also be apparent that the plate 10 being so mounted is thus adapted to cooperate with rolls 3 of varying character.

As a result of my improvements, it is made possible, while obtaining the above advantages, also to produce the plates very inexpensively as compared with the solid plates heretofore provided. Thus, for example, my improved plates 10 and 16 may be stamped from sheet metal without requiring the machining heretofore necessary. Further, by making both edges of the plate 10 of the same construction, the latter may be very readily assembled or reversed. The two-piece construction of the parts 10 and 16 also makes it possible to replace either of these elements independently of the other when desired. These and other advantages of my improvements will, however, be apparent to those skilled in the art.

While I have in this application described one embodiment which my invention may assume in practice, it will be understood that the same is shown for purposes of illustration, and that the invention may be modified and embodied in various other forms without departing from its spirit or the scope of the appended claims.

What I claim as new and desire to secure by Letters Patent is:

1. In a spinning frame, cooperating front drafting rolls, and resilient yarn engaging means flexed against the upper front roll for supporting and pressing the yarn against said roll as the yarn passes from between the nip of said rolls.

2. In a spinning frame, cooperating front drafting rolls, and elongated yarn engaging and supporting means extending from adjacent the nip of said rolls across beneath the top front roll and having a flexible portion pressing the yarn against the bottom of the latter roll.

3. In a spinning frame, cooperating front drafting rolls, and mechanism for divorcing the twisting of the yarn from the drafting function of said rolls including a resilient pressure plate flexed by and conforming to the bottom of the top front roll.

4. In a spinning frame, cooperating front drafting rolls, and mechanism for divorcing the twisting of the yarn from the drafting function of said rolls including a resilient pressure plate

conforming to the bottom of the top front roll and having longitudinally spaced end supports.

5. In a spinning frame, cooperating front drafting rolls, and mechanism for divorcing the twisting of the yarn from the drafting function of said rolls including a resilient pressure sheet flexed by and conforming to the bottom of the top front roll and having a bent extension forming a yarn support during twisting.

6. In a spinning frame, cooperating front drafting rolls, and mechanism for divorcing the twisting of the yarn from the drafting function of said rolls including a resilient pressure sheet conforming to the bottom of the top front roll having depending ends and an underlying supporting member having its ends received in said ends.

7. In a spinning frame, cooperating front drafting rolls, and mechanism for divorcing the twisting of the yarn from the drafting function of said rolls including a resilient pressure plate conforming to the bottom of the top front roll, and longitudinally spaced end supports therefor including an underlying supporting member supporting the ends thereof.

8. In a spinning frame, cooperating front drafting rolls, and mechanism for divorcing the twisting of the yarn from the drafting function of said rolls including a resilient pressure plate conforming to the bottom of the top front roll and having longitudinally spaced depending extensions at its ends, and an underlying supporting member having its ends slidably carrying said extensions.

9. In a spinning frame, cooperating front drafting rolls, and mechanism for divorcing the twisting of the yarn from the drafting function of said rolls including a resilient pressure plate conforming to the bottom of the top front roll and having longitudinally spaced depending extensions at its ends, and an underlying supporting member having upturned ends supported by said depending extensions and supporting opposite ends of said pressure plate.

10. In a spinning frame, cooperating front drafting rolls, and mechanism for divorcing the twisting of the yarn from the drafting function of said rolls including a resilient pressure plate conforming to the bottom of the top front roll and having longitudinally spaced ends, an underlying supporting member supporting the ends of said pressure plate, a pressure frame carrying said supporting member and biasing said plate into operative position, and a universal joint between said supporting member and frame.

11. In a spinning frame, cooperating front drafting rolls, and mechanism for divorcing the twisting of the yarn from the drafting function of said rolls including a resilient pressure sheet conforming to the bottom of the top front roll, a supporting sheet underlying said pressure sheet and having its ends supporting the ends of said pressure sheet, and connections between the ends of said plates for permitting relative movement between said sheets upon variations in flexing of said pressure sheet.

12. A pressure member for spinning frames comprising a resilient yarn supporting and pressing plate having supports at its ends, and an intermediate resilient portion adapted to be flexed by and conform to the surface of a roll.

13. A pressure member for spinning frames comprising a resilient yarn supporting and pressing plate having supports at its ends and having

an outwardly and downwardly curved yarn supporting extension at one end.

14. A pressure mechanism for spinning frames comprising a resilient yarn supporting and pressing plate having supports at its ends and an intermediate resilient portion adapted to be flexed by and conform to the surface of a roll, and supporting means for said plate supporting said ends.

15. A pressure mechanism for spinning frames comprising upper resilient and lower more rigid supporting members disposed in spaced relation and connected at their ends and having said pressure member adapted to flex between its ends toward and from said supporting member.

16. A pressure mechanism for spinning frames comprising a resilient yarn supporting and pressing plate having supports at its ends and an

intermediate resilient portion adapted to be flexed by and conform to the surface of a roll, and supporting means for said plate having means supporting said ends while permitting movement of said ends relative to said supporting means during flexing of said plate.

17. A pressure mechanism for spinning frames comprising a resilient yarn supporting and pressing plate having supports at its ends, an intermediate resilient portion adapted to be flexed by and conform to the surface of a roll, and depending rounded extensions having inturned flanges spaced below said pressure plate, and a supporting plate spaced below said pressure plate and supported by said flanges and having upstanding portions thereon supporting the ends of said pressure plate.

WALTER S. EASTMAN.
